(57) **CLAIM**

The ornamental design for a pad holder, as shown and described.

DESCRIPTION

FIG. 1 shows a bottom view of a first embodiment of my design for a pad holder;

FIG. 2 shows a top view thereof;

FIG. 3 shows a rear view thereof;

FIG. 4 shows a front view thereof;

FIG. 5 shows a right side view thereof with the left side view being identical;

FIG. 6 shows a perspective view thereof;

FIG. 7 shows a bottom view of an alternate embodiment of my design for a pad holder;

FIG. 8 shows a top view of the embodiment of FIG. 7;

FIG. 9 shows a rear view of the embodiment of FIG. 7;

FIG. 10 shows a front view of the embodiment of FIG. 7;

FIG. 11 shows a right side view of the embodiment of FIG. 7 with the left side view being identical; and,

FIG. 12 shows a perspective view of the embodiment of FIG. 7.
